(57) **CLAIM**

The ornamental design for a chair, as shown and described.

DESCRIPTION

FIG. 1 is a perspective view of a first embodiment of a chair according to the present invention;

FIG. 2 is a front-elevational view of the chair of FIG. 1; FIG. 3 is a rear elevational view of the chair of FIGS. 1 and 2;

FIG. 4 is a side-elevational view of the chair of FIGS. 1-3, the other side view being a mirror image thereof;

FIG. 5 is a top plan view of the chair of FIGS. 1-4; and, FIG. 6 is a bottom plan view thereof.
